CLAIM

The ornamental design for a bracket for attaching wine bucket to a table, as shown and described.

DESCRIPTION

FIG. 1 is a top plan view of my new bracket for attaching wine bucket to a table;

FIG. 2 is a front elevational view thereof;

FIG. 3 is a left side elevational view thereof which is a mirror image of a right side elevational view;

FIG. 4 is a rear elevational view thereof; and

FIG. 5 is a bottom plan view thereof.
